United States Patent Office.

JOB JOHNSON, OF BROOKLYN, NEW YORK.

Design No. 4,371, dated September 27, 1870.

DESIGN FOR THE CRADLE-PLATE OF GATE-LATCHES.

The Schedule referred to in these Letters Patent and making part of the same.

To all whom it may concern:

Be it known that I, JOB JOHNSON, of Brooklyn, in the county of Kings and State of New York, have produced a new Design for the Cradle-Plate of Gate-Latches, and the following is declared to be a correct description thereof.

This invention relates to the design of the shape and configuration of the latch or cradle-plate, marked *e* in the patent of Johnson & Ingersoll, assigned to Johnson, granted June 14, 1870, and numbered 104,320.

The shape and configuration of said plate are shown in the accompanying drawing, wherein—

Figure 1 is an elevation, and

Figure 2 is a section, at the line *x x*.

The upper part of the plate is arched, the lower part nearly straight, and at each side the plate is

spread nearly semicircularly, as at *o o*, for the reception of a screw-hole.

This shape and configuration is made for the useful object of gaining strength at the two sides of the plate, where the concussion occurs, adjacent to the projections *o'* and screw-holes.

The shape and configuration of the opening *p* in said plate are similar to that in aforesaid patent.

I claim as my invention—

The design of the shape and configuration of the cradle-plate, substantially as shown.

Signed by me this 31st day of August, A. D. 1870.
JOB JOHNSON.
